UNITED STATES PATENT OFFICE.

ROSWELL T. SMITH, OF NASHUA, NEW HAMPSHIRE.

EMBROIDERING-MACHINE.

SPECIFICATION forming part of Letters Patent No. 377,412, dated February 7, 1888.

Application filed March 30, 1887. Serial No. 233,028. (No model.)

To all whom it may concern:

Be it known that I, ROSWELL T. SMITH, a citizen of the United States, residing at Nashua, in the county of Hillsborough and State of New Hampshire, have invented certain new and useful Improvements in Embroidering-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My present invention relates to embroidery mechanism, and the purpose thereof is to combine with the devices by which the stitch formation is effected a simple and exact apparatus for giving the successive stitch adjustments to the tambour-frame automatically, the invention being for this purpose closely allied to that contained in applications filed by me upon the 10th day of June, 1885, Serial No. 168,237, the 9th day of July, 1886, Serial No. 207,609, the 25th day of March, 1887, Serial No. 232,375, and the 26th day of March, 1887, Serial No. 232,552.

It is a purpose of my invention, also, to provide simple and inexpensive mechanism having positive action whereby mechanical adjustment may be given to any desired extent and in any plane, such adjustments being effected in a predetermined order and time and being wholly automatic. The invention therefore contemplates the application to general mechanical purposes of an automatic attachment whereby a great variety of results may be accomplished, and in this respect it resembles the apparatus described in my application filed March 25, 1887, No. 232,375, the characteristic difference being in the employment of pneumatic power as the motive force.

Another feature of the invention is the organization by which it may be attached without essential change to different mechanisms—such, for example, as the power embroidery-machines referred to in my applications of 1885 and 1886, the embroidery sewing-machine shown in my application of March 30, 1887, No. 233,029, and other machines of different character and for varied purposes.

The invention consists in the several novel features of construction and new combinations of parts, hereinafter fully set forth, and definitely pointed out in the claims following this 55 specification.

Referring to the drawings accompanying this application, Figure 1 is a view, partly in vertical section and partly in elevation, illustrating my invention. Fig. 2 is a transverse 60 vertical section of part of Fig. 1 in the line xx . Fig. 3 is an enlarged view of part of the pneumatic chest shown in Fig. 1 in section. Figs. 4 and 4^a represent, respectively, the manner of preparing the governing-stencil from a 65 chart upon which the several mechanical adjustments are drawn in a manner to illustrate their relative direction and extent.

In the said drawings, the reference-numeral 1 designates a base, of any suitable form, 70 which gives support to the adjusting elements. A convenient construction for this frame is that shown, in which brackets 2 are mounted on the base 1, said brackets having ears 3, in which the parts to which movement 75 is given may freely slide. As a familiar illustration of the capacities of the apparatus, I have shown these parts as consisting of bars 4, each having two racks, 5, with teeth of opposite pitch. These bars are alike in all points, save 80 their movement is in lines at right angles to each other. The mechanism being particularly adapted to effecting the stitch adjustments in embroidery-machines, these movements are shown as being in parallel horizontal planes; but it will be seen that they may be effected in planes at any angle with relation to each other.

Upon the lower part of each bracket is fulcrumed at the point 6 a bell-crank lever, 7, 90 having the vertical arm terminating near the toothed portion of the bar and the horizontal arm 8 lying in the same vertical plane with the bar. The compact organization of the parts is promoted by bringing the extremities 95 of the horizontal arms into or past the same horizontal line, as shown in Fig. 1, for a purpose presently to be shown.

The bar moving at right angles in Fig. 1 is in all particulars similar to that already described, and it is similarly mounted and toothed, while the actuating bell-cranks are duplicates.

of those already described, the extremities of their horizontal arms being arranged in or nearly in the same vertical plane, passing through the like extremities of bell-cranks. 5 (Seen in side elevation.)

Upon the end of the vertical arm of each bell-crank is pivotally mounted a pawl, 9, having a spring, 10, connected to its tail, by which it is normally impelled to engage with 10 the overhanging rack 5 of the bar 4. By the vibration, therefore, of one or the other of said bell-cranks the said bar will be adjusted longitudinally in its bearings 3, the extent of adjustment being proportioned to the number 15 of times the vibrations of the lever are repeated. Between the pawl and the bar is mounted a relief-plate, 11, attached to an arm, 12, of the bracket 2, and adjusted thereon by means of a set-screw, 13, passing through a 20 slot, 14, in the plate. The end of this plate is so adjusted between the nose of the pawl and the rack 5 that when the former is about to cease its retractile movement its nose rides up on the plate and the engagement with the 25 rack ceases. This construction is the same with each bell-crank pawl, and by it the adjustment in opposite directions is rendered possible. These relief-plates also afford convenient means of lengthening or shortening 30 the effective throw of the pawls, since they may be adjusted in the direction of such movement, so that no engagement will be made with the rack until this pawl has so nearly completed its stroke that its remaining movement 35 will adjust the bar the distance of a single tooth only.

The numeral 15 denotes a pneumatic chest constructed of any suitable material—such as wood or metal—and of any convenient size, 40 due regard being had to the power it is expected to possess. The interior of this chest is provided with an exhaust-chamber, 16, occupying usually more than half the cubic space available. Lying within this exhaust-chamber are rigid shelves 17, each having an air-chamber, 18, from which an air-passage, 19, leads to the outer air, said passages being formed in the solid head 15^a of the chest and being so constructed that their orifices lie in 45 substantially the same line.

Covering each air-chamber 18 is a diaphragm, 20, of flexible material, and so applied that it may rise and fall as the equilibrium of atmospheric pressure is disturbed on 50 one side or the other of said diaphragm. On each diaphragm is mounted a piston-disk, 21, having a small air-opening, 22, which opening also passes through the diaphragm, and rigidly connected with each piston-disk 21 55 is a lever, 23, fulcrumed in the remote wall of the chest, or on any suitable support removed from the air-chambers 18. The chamber 16 is exhausted by any ordinary blower or pump communicating with said chamber by a pipe, 24. 60

65 In the solid head 15^a of the air-chest is journaled a shaft, 25, carrying a sprocket, 26, the teeth 27 whereof project beyond the end of the

solid head, in which the orifices of the air-passages 19 lie. This sprocket is driven with an intermittent rotation produced by a pitman, 70 28, which vibrates a pawl-carrying arm, 29, mounted on the end of the sprocket-shaft 25 and carrying a pawl, 30, which is engaged with the teeth of a ratchet, 31, on the shaft 25. The pitman 28 is provided with two adjustable nuts, 32 and 33, which make engagement alternately with the bearing 34, in which the pitman reciprocates. These nuts alternately retract the pawl-carrier 29 and then project it forward, thus giving to the sprocket a progressive revolution with an interval of rest after each advance, such interval being proportioned to the distance between the adjustable nuts and the speed of the pitman. A wrist-pin, 35, carried by a disk, 36, gives reciprocation to the pitman, the disk 36 being driven by a pulley, 37, belted to any source of power. 80

Over the end of the solid head of the pneumatic chest is carried a stencil-sheet, 38, having a central series of openings, 39, which engage with the teeth of the sprocket 26. In this pitman are formed at intervals openings 40, arranged in different longitudinal series, having such location in the stencil that as the latter advances said openings may pass over 90 and register with the mouths of the air-passages 19. By reference to Fig. 3 it will be seen that as any one of the stencil-openings uncovers the orifice of one of the air-channels 19 the air-pressure beneath the diaphragm 20 100 will be in excess of that upon the other side of the diaphragm. The latter will therefore rise and lift the piston-disk 21. A like movement will be communicated to any one of the four piston-disks in turn, the time of their relative 105 movements being determined by the arrival of the openings 40 in the stencil at the mouths of the air-passages 19.

Upon each of the levers 23 is mounted a rod, 41, which projects upward through the wall of 110 the pneumatic chest and has its end set in a bearing on the horizontal arm of one of the bell-cranks 7. The arrangement of these rods is shown in Fig. 2, from which it will be seen that they correspond with the alignment of the 115 parts of the levers with which they engage. By carrying the shelves 17 entirely across the chest I am able to arrange the piston-disks 21 partly beneath each other, and at the same time give ample proportions to each, the rods and 120 disks being connected in an ascending series, which allows them to be brought as close as may be necessary.

To illustrate the infinite variety of automatic action of which the apparatus is capable, I have shown in Fig. 4^a one form of stencil whereby the successive mechanical adjustments indicated in Fig. 4 may be accomplished. 125

If the pattern-sheet in Fig. 4 represents spaces of, say, one-tenth of an inch each, and 130 the outline thereon is that of a leaf to be indicated on the stencil, it will be readily seen how the latter is constructed from the former. The stencil being laid off in equal spaces 42, each

indicating a space proportioned to one of the squares of the pattern, it will be noted that the initial movement in the charted design is diagonally across one of the squares. Considering this as a stitch to be formed on an embroidery-machine, it is evident that a single move to the right and an equal movement upward will exactly represent such a stitch. Therefore on the stencil the cuttings in space 1 are in the "up" and "right" series. Stitches Nos. 2 and 3 are similar, but the fourth is upward and to the left. Therefore this is represented in the stencil by cuttings in the series marked No. 5, one in the up and one in the "left" longitudinal series. By tracing the design further it may be seen that the pattern can be as easily read on the stencil as on the design itself, and that by a simple variation of arrangement any series of adjustments may be readily effected with a most exact automatic action. It should be noted that this stencil is cut in such manner that when used upon an embroidering mechanism it will give equal adjustments at each advance of the stencil, the stitch formation alternating therewith and working the design in stitches of equal length. It is evident, however, that by providing for a repeated action of the stencil between successive stitches a design may be executed in stitches of unequal length, as shown in my application filed March 25, 1887, No. 232,375.

In working trade-marks, also, by a mechanism similar to that shown in my application filed March 30, 1887, Serial No. 233,029, this apparatus may be attached to the tambour-adjusting bars without change, the feed of the stencil being so timed that its adjustments will alternate with the stitch formation and give a continuous action. The effective throw of each bell-crank 7 may be varied by set-screws 43, which arrest the vibration. This same result may be secured by slightly extending the bearing for the pivotal fulcrum 6 and forming a series of openings therein. By pivoting the lever 7 nearer the rods 41 the latter will approach the fulcrum-point and the stroke will be correspondingly increased. The bell-cranks are each retracted by springs 44.

It is important to notice that by building up the pneumatic chest in ascending series as regards the separate air-chambers 18 I am able to give any desired size to the piston-surface within the available space in the chest, and still bring the rods 41, actuated by the lift of said pistons, close together. The piston-surface may thus be increased as the needed power may require without affecting the relative arrangement of the rods and other parts actuated by said piston.

What I claim is—

1. The combination, with an adjustable bar, of reciprocating devices having alternate intermittent engagement therewith and imparting step-by-step motion thereto and pneumatic pistons actuating said devices, said pistons being operated by a disturbance of the

equilibrium of air-pressure on their opposite sides, effected by a traveling stencil having air-openings which communicate as the stencil 70 advances with the chambers in which said pistons lie, substantially as specified.

2. The combination, with two or more bars having longitudinal adjustment, of reciprocating devices giving intermittent longitudinal adjustment, a pneumatic chest having pumping mechanism communicating with it, pistons interposed in air-passages leading from the exterior to said chest, and a stencil traveling over the mouths of said air-passages, 80 said pistons being connected to the reciprocating devices, substantially as specified.

3. The combination, with a pneumatic chest having an exhaust-chamber and provided with successive shelves lying in said chamber, 85 of pistons lying in air-chambers in said shelves, passages connecting said chambers with the outer air, a stencil traveling over said passages and having varied openings, and rods lifted by the pistons, substantially as specified.

4. The combination, with a pneumatic chest having an exhaust-chamber and provided with shelves which are arranged within said chamber, each shelf having an air-chamber communicating with the exterior, of a series 95 of pistons, one in each air-chamber, levers fulcrumed on a suitable support and attached to said pistons, devices rising and falling with said levers, and a stencil traveling over the passages connecting the piston-chamber with the exterior air, said stencil having openings in four separate series, substantially as specified.

5. The combination, with the bars arranged as set forth, of the reciprocating bell-cranks 105 adjusting said bars, a series of rods engaging said bell-cranks, a pneumatic chest having a series of shelves arranged in its interior, a series of air-chambers partly overlying each other in said shelves, piston-disks lying in 110 said chambers, a stencil moving over air-passages communicating with said air-chambers, and means for exhausting the chest, the rods engaging the bell-cranks being actuated by the rise of said piston-disks, substantially as 115 specified.

6. The combination, with a pneumatic chest having an exhaust chamber and provided with separate air-chambers communicating with the exhaust and with the exterior air, 120 of diaphragms covering said air-chambers, pistons mounted on said diaphragms and having openings in the diaphragms, and a stencil having four series of openings which register with the passages connecting the piston-chambers with the exterior, said chambers being arranged in an ascending order, substantially as specified.

7. The combination, with the pneumatic chest having an exhaust-chamber and provided with separate air-chambers, of piston-disks lying in said chamber, levers fulcrumed to suitable supports and attached to said piston-disks, a stencil lying upon the solid head

of the chest and having varied openings, a feed-sprocket journaled in the solid head, and means for operating said sprocket to advance the stencil, openings being formed between the piston-chambers and the stencil and in said pistons, substantially as specified.

8. The combination, with the adjustment mechanism composed of the toothed bars, the bell-cranks, and the pawls carried thereby, of a pneumatic chest, air-chambers therein communicating with an exhaust-chamber and with the exterior, piston-disks lying in said air-chambers, levers operated thereby, a stencil having varied openings arranged in four series, and means for exhausting the chest and feeding the stencil, a small opening being formed in each piston to establish an equilibrium of pressure on both sides thereof, substantially as specified.

20 9. A pneumatic chest having a main air-chamber and provided with a series of sepa-

rate air-chambers which communicate with the main chamber and with the exterior, in combination with a series of pistons and piston-disks lying in said separate air-chambers, 25 and rods which are actuated by the lift of said pistons, the separate air-chambers being arranged to partly overhang each other, or in an ascending series, whereby the rods operated by the piston may be brought into close 30 proximity, and the piston-disks being controlled in their action by a stencil moving over the air-openings which connect the separate air-chambers with the exterior, substantially as specified.

In testimony whereof I affix my signature in presence of two witnesses.
